POKER CHIP RACK

Larry Allen, North Hollywood, Calif.

Application February 9, 1959, Serial No. 54,527

Term of patent 14 years

(Cl. D34—5)

I claim:

The ornamental design for a poker chip rack, as shown.
